UNITED STATES PATENT OFFICE.

FREDERIC L. DEWEY, OF CANTON, ILLINOIS, ASSIGNOR TO PARLIN & ORENDORFF COMPANY, OF CANTON, ILLINOIS, A CORPORATION OF ILLINOIS.

CULTIVATOR.

1,253,359.

Specification of Letters Patent. Patented Jan. 15, 1918.

Application filed June 9, 1917. Serial No. 173,864.

To all whom it may concern:

Be it known that I, FREDERIC L. DEWEY, a citizen of the United States, and a resident of Canton, in the county of Fulton, 5 State of Illinois, have invented certain new and useful Improvements in Cultivators, of which the following is a specification, reference being had to the accompanying drawings.

10 This invention relates to improvements in cultivators and particularly to that class of riding cultivators in which the wheels are adapted to be turned at an angle for guiding the machine, the turning of the wheels for 15 directing the machine in one direction having the effect of moving the shovel gangs relative to the frame in the same direction; and in which the wheels are adapted to be moved rearwardly relative to the frame 20 when the shovel gangs are raised simultaneously for making the turn at the end of a row or for transportation of the machine from one point to another. It is the object of my invention to provide a new 25 and improved form and arrangement of connections between the shovel gangs and the frame whereby the desired movements of the gangs may be attained with great facility and with a minimum expenditure of 30 force in the operation. It is another object of my invention to provide a new and improved form and arrangement of means for holding the shovel gangs in adjusted position laterally relative to each other whereby. 35 the distance between the gangs may be very readily regulated as may be desired. It is another object of my invention to provide a new and improved form and arrangement of framework which shall be particularly 40 adapted to the requirements of a plow of this type and which shall also be capable of ready adjustment laterally for varying the distance between the carrying wheels. It is another object of my invention to improve 45 cultivators in sundry details hereinafter pointed out. The preferred means by which I have accomplished my several objects are illustrated in the drawings and are herein-after specifically described. That which I 50 believe to be new and desire to cover by this application is set forth in the claims.

In the drawings:

Figure 1 is a side view of a cultivator embodying the preferred form of my improved construction;

Fig. 2 is a top or plan view of the cultivator shown in Fig. 1;

Fig. 3 is a view similar to Fig. 1, but showing the parts in changed position, the gangs having been raised in unison with 60 the consequent backward shifting of the carrying wheels;

Fig. 4 is a view similar to Fig. 2, but showing the gangs moved toward one side and the carrying wheels turned at an angle 65 so as to carry the cultivator as a whole in the same direction;

Fig. 5 is an enlarged detail, being a fragmentary view at one side of the machine showing the construction of the arch of the 70 frame of the cultivator;

Fig. 6 is an enlarged detail of the lever for adjusting the shovel gangs laterally relative to each other, being partly in section taken substantially on line 6—6 of Fig. 2; 75

Fig. 7 is an enlarged detail, being substantially a section taken on line 7—7 of Fig. 6;

Fig. 8 is an enlarged detail, being substantially a section taken on line 8—8 of 80 Fig. 4; and

Fig. 9 is an enlarged detail, being substantially a section taken on line 9—9 of Fig. 4.

Referring to the several figures of the 85 drawings in all of which corresponding parts are indicated by the same reference characters,—

15 indicates the forward transversely-extending bar of the framework of the machine having fixedly connected thereto the side bars 16—17 of the frame, the side bars 16—17 being turned inward at their forward ends into engagement with the sides of a pole or tongue 18 which is fixedly connected at its rear end with the bar 15. At 90 their rear ends the side bars 16—17 are fixedly connected by means of brackets 19 with the end portions of a transversely-extending pipe or bar 20, the brackets 19 comprising split sleeve portions as is shown 95 in Figs. 1 and 3 for fixedly connecting them 100

to the pipe 20. A seat 21 is supported in position from the main frame by means of bars 22-23 which are connected at their forward ends to the side bars 16-17 as is shown in Figs. 2 and 4, the bars 22-23 being supported in rear of their connection with the bars 16-17 by reason of their resting upon the cross-bar 20.

As will be understood from an inspection 10 of Fig. 5, the cross-bar 20 comprises the major portion of the horizontally-extending bar of the main frame arch, the arms of the arch being provided by means of angled bars 24-25, the horizontally-extending portions 15 of which are revolubly mounted in the respective ends of the pipe or bar 20. The horizontally-extending portions of the bars 24-25 are revolubly and adjustably held in position in the ends of the pipe 20 by means 20 of collars 26 adjustably mounted in position upon said bars by means of set-screws 27, the collars 26 being provided with fingers 28 the ends of which are turned about ribs 29 forming parts of the brackets 19. By 25 loosening the set-screws 27, the bars 24-25 can be adjusted laterally as may be desired, being secured revolubly in adjusted position by a subsequent tightening of the screws 27.

30 Carrying wheels 30-31 are mounted upon the framework by being journaled upon laterally-extending portions of axle members 32-33 respectively. The axle members 32-33 are mounted upon the main frame 35 arch comprising the bars 20, 24 and 25 by means of sleeves 34 to which the axle members are fixedly secured by means of bolts passing through lugs 35 extending from said sleeves at one side. The sleeves 34 are 40 journaled upon the vertically-extending portions of the bars 24-25, being held revolubly in position thereon by means of cotter-pins 36 at their lower ends and split collars 37 at their upper ends. The upper end portions 45 of the axle members 32-33 are turned to extend forwardly, the front ends of the forwardly-extending arms being connected by means of a transversely-extending bar 38. The bar 38 is provided with a plurality 50 of holes therethrough for the connection of the axle members 32-33 to provide for the lateral adjustment of the wheels 30-31 as has been above described. The vertically-extending portions of the axle members 55 32-33 are provided with inwardly-extending arms or foot levers 39-40, such foot levers being secured in position in the construction shown by means of eye-bolts 41 as is best shown in Fig. 5. As will be appreciated, the operator in position upon the seat 21 is able by pressure upon one or the other of the foot levers 39-40 to swing both of the sleeves 34 about the vertically-extending portions of the arms 24-25 for turning the

wheels 30-31 at an angle relative to the 65 framework for steering the machine toward either side as may be desired. By applying a preponderance of force to the foot lever at one side while at the same time applying sufficient power to the foot lever at the opposite side for controlling the turning movement, the position of the wheels 30-31 may be regulated to a nicety.

70 The means for holding the arch members 24-25 and the carrying wheels 30-31 in 75 adjusted position longitudinally of the machine comprises a rock-shaft 42 journaled in position across the main frame of the cultivator. The rock-shaft is held in adjusted position by means of a lever 43 80 fixedly mounted upon one end portion of the rock-shaft, the lever 43 being adjustable along a segmental rack 44 fixedly mounted in position upon the framework. The rock-shaft 42 is provided at its ends 85 with downwardly-extending arms 45-46 fixedly mounted thereon, the lower ends of said arms being pivotally connected by rigid links 47-48, respectively, with the sleeves 34 carried by the vertically-extending arms 90 of the main frame arch. When the lever 43 is given an upward movement from the position shown in Fig. 1 into the position shown in Fig. 3, the arms 45-46 are given a movement in clockwise direction in Figs. 95 1 and 3, serving through the medium of the links 47-48 to move the sleeves 34 backward, serving to carry the wheels 30-31 backward relative to the framework.

100 The means for mounting the shovels adjustably upon the frame of the machine comprises a transversely-extending bar 49 the ends of which are fixedly connected to brackets 50-51 as is clearly shown in Figs. 2 and 4. The brackets 50-51 are provided 105 with downwardly-extending arms 52-53, respectively, the lower ends of which are pivotally connected to links 54-55 which are pivotally connected at their upper ends to the frame-bar 15 as is clearly shown in 110 Figs. 1 and 3. The brackets 50-51 are also provided with rearwardly-extending arms 56-57 fixedly connected thereto, the rear ends of the arms 56-57 being connected by means of eye-bolts 58 with the transversely-extending bar 38. By reason of the cross-bar 49 being supported by the links 54-55 which are adapted to swing laterally, and by the arms 56-57 connected with the laterally-movable bar 38, it will be understood 115 that the bar 49 is adapted to have a free and easy lateral movement with the bar 38, the arms 56-57 causing the bars 38 and 49 to move in unison.

120 Sleeves 59-60 slidably mounted upon the transversely-extending bar 49 are adjustable along said bar by the means hereinafter described. Each of the sleeves 59-60 is fix-

edly connected in any appropriate manner with shovel bars 61-62 which are provided with shovels 63 of any suitable type mounted thereon by any suitable means, the construction and arrangement being such that each of the gangs of shovels is adjustable vertically about the transversely-extending bar 49. The bars 62 at opposite sides of the plow are connected by links 64-65 with vertically-extending bars 66 which are connected at their upper ends to the outer ends of a cross-bar 67.

The means for swinging the shovel gangs about the bar 49 comprises levers 68-69 revolvably mounted upon the rock-shaft 42, such levers being connected by means of links 70 with cross-bars 71 joining the bars 61-62 of the gangs. As is shown in Fig. 8, the lower ends of the links 70 pass through suitable openings in the bars 71, being provided with cotter pins 72 at their lower ends so as to prevent withdrawal of the links 70. Compression springs 73 about the link 70 bear at their lower ends upon the bars 71 and at their upper ends against collars 74 carried by the links 70. Thus upon a movement of the levers 68-69 in clockwise direction in Figs. 1 and 2, the shovel gangs are raised through the medium of the links 70. When the levers 68-69 are held in lowered position as shown in Fig. 1, the gangs of shovels are held yieldingly also in lowered position through the medium of the springs 73. The levers 68-69 are adapted to be adjustably connected with the rock-shaft 42 upon which they are revolvably mounted, this adjustable connection being effected through the medium of segmental racks 75-76 fixedly mounted upon the rock-shaft 42 adjacent to the levers 68-69, the levers being provided with latch mechanism of any approved type for adjustably engaging said segmental racks respectively.

By the construction above described, the gangs may be adjusted vertically through the medium of the levers 68-69 independently of each other, or they may be adjusted vertically in unison upon the turning of the rock-shaft 42 through the medium of the lever 43 as above described, the arrangement being such that the shovel gangs are raised as the wheels 30-31 are shifted backward and are again lowered when the wheels are moved forward to normal operative position. In order to assist in raising the gangs either separately or in unison, and to assist in the backward shifting of the wheels when the gangs are raised in unison, I have provided springs 77-78 connected at their rear ends to the levers 68-69, respectively, and at their forward ends to the bar 15, the springs serving to exert a pull on the levers for assisting in the gang-raising operation.

The means for adjusting the sleeves 59-60

laterally relative to each other along the bar 49 for adjusting the distance between the shovel gangs comprises a bracket 79 revolvably mounted upon the bar 49, but held against movement longitudinally of said bar. The bracket 79 is provided at its free end portion with a sleeve 80 upon the ends of which a lever 81 is pivotally mounted, the lever being braced laterally by an arm 82 forming with the lever substantially a yoke construction. The bracket 79 has fixedly connected therewith a segmental rack 83 by which the lever 81 is adapted to be held in adjusted position relative to the bracket. The rack-bar 83 is supported by engagement with the rock-shaft 42, and the bracket 79 is prevented from moving upward out of position by a finger 84 preferably formed with the bracket 79 and extending under the rock-shaft 42. It will be understood that the bracket 79 and the lever 81 and connected parts are adapted to move laterally with the bar 49 relative to the rock-shaft 42. The lower ends of the arms of the yoke formed by the lever 81 and the arm 82 have revolvably mounted therein a transversely-extending sleeve 85 which is held against movement longitudinally of itself by the turned ends of pivotally mounted links 86-87 which extend through suitable openings in the ends of the sleeve 85, the links being prevented from withdrawal by cotter-pins 88. The links 86-87 extend forward from the sleeve 85 in diverging position, the outer ends of said links being pivotally connected with the sleeves 59-60, respectively, as is best shown in Fig. 9. When the transverse bar 38 is shifted laterally for turning the wheels at an angle, serving to carry the bar 49 and the shovel gangs laterally therewith, the bracket 79, the lever 81 and their coöperating parts are moved laterally therewith. Whenever it is desired to adjust the distance between the shovel gangs, this is accomplished by a stroke of the lever 81 in one direction or the other, serving to vary the distance of the sleeve 85 from the bar 49 and serving thus through the diagonally-extending links 86-87 to adjust the sleeves 59-60 laterally relative to the bar 49. As will be readily understood, when the lever 81 is given a movement in clockwise direction in Figs. 1, 3 and 6 so as to carry the sleeve 85 away from the bar 49, the shovel gangs will be moved toward each other. When on the other hand the lever 81 is given a movement in counterclockwise direction in Fig. 6 so as to move the sleeve 85 toward the bar 49, the sleeves 59-60 and the shovel gangs carried thereby will be moved away from each other.

As will be readily understood, the bar 49, the brackets 50-51 fixedly connected thereto, and the arms 52-53 in turn fixedly con-

nected to the brackets 50—51, constitute in effect a transversely-extending arch upon the crossbar of which the gangs are mounted. So far as I am aware, I am the first in 5 the art to provide a transversely-extending arch with the gangs mounted upon the crossbar of such arch, the arch being supported in position only by a single pair of swinging links such as the links 54—55 and by 10 connections to laterally-movable arms such as the forwardly-extending arms of the axle-members 32—33 by which the carrying wheels are turned at an angle relative to the frame, and my claims are to be construed 15 accordingly.

What I claim as my invention and desire to secure by Letters Patent, is—

1. In a cultivator, the combination of a frame, a bar extending transversely of said 20 frame, brackets connected to the end portions of said bar, arms fixedly connected to said brackets and depending therefrom, links pivotally connecting the lower ends of said arms with said frame whereby said bar is 25 movable laterally relative to said frame, carrying wheels journaled on said frame and adapted to be turned at an angle relative to the frame, laterally-shiftable means connecting said carrying wheels for holding 30 them in parallelism as they are turned at an angle relative to the frame, other arms connecting said bar with said laterally-shiftable means, and shovel gangs connected with said bar and adapted to be shifted laterally there- 35 with.

2. In a cultivator, the combination of a frame, a bar extending transversely of said frame, brackets connected to the end portions of said bar, arms fixedly connected to 40 said brackets and depending therefrom, links pivotally connecting the lower ends of said arms with said frame whereby said bar is movable laterally relative to said frame, carrying wheels journaled on said frame and 45 adapted to be turned at an angle relative to the frame, a laterally-extending bar connecting said carrying wheels for holding them in parallelism as they are turned at an angle relative to the frame, other arms pivotally connected with said second-named bar and fixedly connected with said brackets for 50 causing said two bars to move laterally in unison, and shovel gangs connected with said first-named bar and adapted to be shifted laterally therewith.

3. In a cultivator, the combination of a frame, an arch extending transversely of said frame, shovel gangs mounted on the transversely-extending bar of said arch, 55 swinging links pivotally connected with said frame and with the depending portions of said arch for permitting the arch to move laterally, a crossbar movable laterally relative to said frame, and connections between

said crossbar and said arch, said connections 65 being rigid laterally for causing said arch to move laterally with said bar.

4. In a cultivator, the combination of a frame, an arch extending transversely of said frame, shovel gangs mounted on the 70 transversely-extending bar of said arch, swinging links pivotally connected with said frame and with the depending portions of said arch for permitting the arch to move laterally, a crossbar movable laterally relative to said frame, arms connected with said arch and extending longitudinally of the machine therefrom, being rigidly mounted for preventing lateral swinging relative to the arch, and pivotal connections between 75 said last-named arms and said last-named crossbar.

5. In a cultivator, the combination of a frame, an arch extending transversely of said frame, shovel gangs mounted on the 80 transversely-extending bar of said arch, swinging links pivotally connected with said frame and with the depending portions of said arch for permitting the arch to move laterally, a crossbar movable laterally relative to said frame, arms rigidly connected with said arch and held against swinging either horizontally or laterally relative to said arch, and pivotal connections between 85 said last-named arms and said last-named crossbar.

6. In a cultivator, the combination of a frame, carrying wheels journaled thereon and adapted to be turned at an angle relative to said frame, a crossbar connecting said 100 carrying wheels for maintaining them in parallelism, an arch extending transversely of said frame, shovel gangs mounted on the transversely-extending bar of said arch, swinging links pivotally connected with 105 said frame and with the depending portions of said arch for permitting the arch to move laterally, and connections between said first-named crossbar and said arch adapted to cause said arch to move laterally with said bar as said wheels are turned at an angle relative to the frame.

7. In a cultivator, the combination of a frame, an arch extending transversely of said frame, shovel gangs mounted on the 110 transversely-extending bar of said arch, and means for supporting said arch upon said frame permitting the arch to move laterally relative to the frame and permitting the arms of the arch to move longitudinally 115 relative to the frame, comprising a pair of links pivotally connected with the frame and with the lower end portions of the arms of said arch.

8. In a cultivator, the combination of a 120 frame, an arch extending transversely of said frame, shovel gangs mounted on the transversely-extending bar of said arch, and

means for supporting said arch upon said frame permitting the arch to move laterally relative to the frame and permitting the arms of the arch to move longitudinally relative to the frame, said supporting means comprising a pair of links pivotally connected with the frame and with the lower end portions of the arms of said arch, other arms extending longitudinally of the machine and adapted to be rocked slightly up and down relative thereto, and means connecting said last-named arms with the crossbar of said arch, said connecting means being held against movement either horizontally or laterally relative to said arch.

9. In a cultivator, the combination of a frame, carrying wheels journaled thereon adapted to be turned at an angle relative thereto, arms extending longitudinally of the machine and adapted to be swung laterally upon the turning of the wheels at an angle relative to the frame, an arch extending transversely of said frame, shovel gangs mounted on the transversely-extending crossbar of said arch, and means for supporting said arch upon said frame permitting the arch to move laterally relative to the frame and permitting the arms of the arch to move longitudinally relative to the frame, said supporting means comprising a pair of links pivotally connected with the frame and with the lower end portions of the arms of said arch, and means connecting the crossbar of said arch with said first-named arms adapted to cause said arch to move laterally relative to the frame as said wheels are turned at an angle relative to the frame.

10. In a cultivator, the combination of a frame, carrying wheels journaled thereon adapted to be moved longitudinally of the frame and adapted to be turned at an angle relative thereto, arms extending longitudinally of the machine adapted to be swung laterally upon the turning of the wheels at an angle relative to the frame and adapted to be rocked up and down relative to the frame as said carrying wheels are moved longitudinally of the machine, an arch extending transversely of said frame, shovel gangs mounted on the transversely-extending crossbar of said arch, and means for supporting said arch upon said frame permitting the arch to move laterally relative to the frame and permitting the arms of the arch to move longitudinally relative to the frame, said supporting means comprising a pair of links pivotally connected with the frame and with the lower end portions of the arms of said arch, and means connecting the crossbar of said arch with said first-named arms, said connecting means being held against movement either horizontally or laterally relative to said arch.

11. In a cultivator, the combination of a frame, carrying wheels journaled thereon adapted to be moved longitudinally of the frame and adapted to be turned at an angle relative thereto, arms extending longitudinally of the machine adapted to be swung laterally upon the turning of the wheels at an angle relative to the frame and adapted to be rocked up and down relative to the frame as said carrying wheels are moved longitudinally of the machine, a crossbar connecting said arms for holding said wheels in parallelism, an arch extending transversely of said frame, shovel gangs mounted on the transversely-extending crossbar of said arch, and means for supporting said arch upon said frame permitting the arch to move laterally relative to the frame and permitting the arms of the arch to move longitudinally relative to the frame, said supporting means comprising a pair of links pivotally connected with the frame and with the lower end portions of the arms of the arch, arms fixedly mounted on the crossbar of said arch and extending toward said first-named crossbar, and means for pivotally connecting said last-named arms with said first-named cross-bar.

12. In a cultivator, the combination of a transversely-extending bar, two shovel gangs connected with said bar and adjustable laterally relative thereto, an arm pivotally mounted on a transversely-extending axis on said bar, means for swinging said arm about its axis, and connections between said arm and said gangs, comprising a short transversely-extending bar revolvably mounted on said arm, and diverging links pivotally connected with said second-named transversely-extending bar and also pivotally connected with said gangs, said diverging links being adapted upon a swinging movement of said arm relative to said first-named bar to adjust said gangs laterally along said first-named bar.

13. In a cultivator, the combination of a transversely-extending bar, two shovel gangs connected with said bar and adjustable laterally relative thereto, a lever pivotally mounted on a transversely-extending axis on said bar, and connections between said lever and said gangs, comprising a transversely-extending sleeve revolvably mounted in said lever, and diverging links pivotally connected at their inner ends with said sleeve and pivotally connected at their outer ends with said gangs, said diverging links being adapted upon a stroke of said lever to adjust said gangs laterally along said first-named bar.

14. In a cultivator, the combination of a transversely-extending bar, two shovel gangs connected with said bar and adjustable laterally relative thereto, a bracket rev-

olubly mounted on said bar but held against lateral movement relative thereto, a lever provided with two arms spaced apart at its lower end portion pivotally mounted on said bracket, a transversely-extending sleeve rev-
5 olubly mounted in suitable bearings in the arms of said lever below said bracket, and diverging links pivotally connected at their

inner ends with said sleeve and connected at their outer ends with said gangs, said di- 10 verging links being adapted upon a move-
ment of the sleeve longitudinally of the ma-
chine as said lever is swung back and forth
to adjust said gangs laterally along said
first-named bar.

FREDERIC L. DEWEY.
